UNITED STATES PATENT OFFICE.

LEWIS W. CONNELL, OF JOLIET, ILLINOIS.

BARB-FENCE-WIRE MACHINE.

SPECIFICATION forming part of Letters Patent No. 325,733, dated September 8, 1885.

Application filed June 22, 1885. (No model.)

To all whom it may concern:

Be it known that I, LEWIS W. CONNELL, a citizen of the United States, residing in Joliet, in the county of Will and State of Illinois, have invented a new and useful Improvement in Barb-Fence-Wire Machines, of which the following is a specification.

This invention relates to barbed fence-wire machines, and more particularly to machines for making that kind of barbed fence-wire wherein but a single strand is employed, the wire-barbs coiled about it being held in place by short kinks or bends formed in the fence strand at intervals where the barbs are attached.

The object of my invention is to produce an automatic machine of a simple and durable construction for rapidly manufacturing such fence-wire, and particularly such fence-wire as I have shown in the accompanying drawings at Fig. 22, the same being also patented in Letters Patent No. 303,406, dated August 12, 1884.

Machines have heretofore been made for manufacturing this fence-wire, as shown in the Reissued Letters Patent No. 10,597, of May 12, 1885, in which machines the kink or bend is first formed in the fence-strand by suitable dies, when the strand is fed forward into position for the coiling-head and the barb then wrapped about the strand at the kink or bend therein. To do good work these machines obviously require extreme accuracy in the feeding mechanism of the fence-strand, else the barbs will not be properly applied at the kinks. In my invention the kink is not formed in the fence-strand until after the barb has been coiled thereon. The barb is cut off before being coiled around the fence-wire, and both its ends are wrapped at once in opposite directions around the strand-wire by two oppositely-revolving coiling heads or fingers. The fence-strand as well as the barb is held in position while the latter is being wrapped around the former by the crimping dies or jaws. After the barb is coiled around the fence-strand a further movement of the dies forms the kink or crimp in the fence-strand. To still further increase the capacity of the machine, two barbs are applied at once. This is accomplished by means of three

coiling-heads, the middle one having a coiling-finger on each end.

In the accompanying drawings, which form a part of this specification, and in which similar letters of reference indicate like parts, Figure 1 is a side elevation of a machine embodying my invention. Fig. 2 is a plan view. Fig. 3 is a section on line 3 3 of Fig. 2. Fig. 4 is an enlarged section on line 4 4 of Fig. 2. Figs. 5, 6, 7, 8, 9, and 10 are enlarged detail views of one pair of the coiling heads or fingers, showing the barb in various stages of its application. Fig. 11 is a section on line 11 11 of Fig. 5. Fig. 12 is a detail view of one of the coiling-fingers. Fig. 13 is an end view of one of the coiling-heads. Fig. 14 is a section on line 14 14 of Fig. 9. Fig. 15 is a central vertical longitudinal section through a portion of the crimping-die and its holder. Fig. 16 is a section on line 16 16 of Fig. 15. Fig. 17 is a section through the rear coiling-head. Fig. 18 is a detail elevation of a pawl-and-ratchet mechanism, through which an intermittent motion is communicated to the gears which drive the coiling heads. Fig. 19 is an enlarged plan view of the strand-wire-feed mechanism. Fig. 20 is a section on line 20 20 of Fig. 2. Fig. 21 is a detail view of a part, hereinafter to be described; and Fig. 22 shows the barbed fence-wire the machine is specially designed to make. Fig. 23 is a detail view showing the mechanism for rotating the feed-wheel shaft.

In said drawings, A represents the frame of the machine, a the fence-wire or strand which is to be barbed, and a' a' the two barb-wires from which the barbs are cut. Each of these wires is supplied from a suitable spool, (not shown in the drawings,) and the finished product or barbed wire a is wound upon a suitable spool, A', at one end of the machine. The fence-wire a is fed or drawn through the machine intermittently by means of an intermittently-revolving feed-wheel, B, on the shaft B'. This feed-wheel has radial forked arms b, which carry or support the strand a, and also radial clamping jaws or arms b' and b'', the arms b'' being pivoted to the cast or rigid arms b' at b'', so as to clamp the strand a between them and pull or feed it forward a certain distance at each movement of the shaft

B' and its wheel B. The arms or jaws b^2 are operated to clamp and release the wire a as the wheel B revolves by means of a fixed cam, b^4 , in the form of a collar surrounding the shaft B', against which the inner ends of the arms b^2 impinge as they revolve around with the wheel B. The ends of the arms b^2 are provided with friction rollers or wheels b^5 , to bear against the face of the cam. The arms b^2 or jaws b^2 may be pressed open when not closed by the cam by means of springs, which may be attached by suitable screws to the wheel B; but these springs need not be used. The cam or collar b^4 is prevented from turning with the shaft B' by the bracket b^8 , attached to the frame, and to which the sleeve of the collar b^4 is attached by the set-screw b^9 . By turning the sleeve of the cam b^4 in the collar b^{10} of the bracket b^8 , the face of the cam may be adjusted to open and close the jaws b^2 at the proper points. The wheel B has four pairs of arms, b^1 , b^2 , and it or its shaft B' is revolved intermittently a quarter-turn each time by means of the ratchet B², secured to said shaft, and the pawl B³, pivoted to and between the arms B⁴, which are mounted loosely on the shaft B', and are swung back and forth by the pitman-rod B⁵, connected to the revolving crank B⁶. A spring, B⁷, serves to press the pawl B³ against the teeth of the ratchet B². The shaft B⁸, to which the crank B⁶ is secured, is driven from the main driving-shaft C through the bevel-gears C' C². Each of the barb-wires a is fed diagonally across the fence-wire a by means of a pivoted feed-lever D, having two clamping-jaws, d and d' , on its upper end, the latter pivoted to the former at d^2 . The levers D are vibrated back and forth on their pivots D' by means of the links d^3 , which are pivoted at one end to the pivotal jaws d' , and at the other to the levers d^4 . The levers d^4 are pivoted at d^5 to the frame A, and are connected at their lower ends to the two branches d^6 of the yoke-lever d^7 by the pivotal links d^8 . The upper end of the yoke-lever d^7 has a pin or roller, d^9 , which fits in the grooved cam d^{10} on the driving-shaft C. As the links d^3 , by which the power is communicated to the feed-levers D, are pivoted directly to the movable jaws d' , these jaws will be opened and release the wires a when the levers D are pulled back by the links d^3 , and closed to clamp the wires a and feed them forward when the levers D are pushed forward. The pivoted jaws d' are each provided with a flange, d^{11} , and set-screw d^{12} , by means of which the amount of slack motion may be regulated and the feed adjusted to the length of barb required. As the levers d^4 and the yoke or branched levers d^6 , d^7 vibrate in planes at an angle to each other, the links d^8 connecting them are provided with pins d^{13} , which fit in eyes d^{14} on the levers, to permit the links to swivel properly. The barb-wires a are each cut off at suitable lengths to form barbs by knives E and E', the former being a stationary one and fixed to the frame of the ma-

chine, and the latter a reciprocating or movable one. The cutting faces or edges of the knives are set at an angle to the direction of the wires a , so as to point the barbs at the same time they are severed. The movable knives E', one for each barb wire a , are rigidly secured in the head F of the lever F', by which said knives are operated. The lever F' and a similar lever, F², are pivoted to the frame on the shaft or pin f, and the two levers are vibrated, to give the requisite movements to the tool-heads F and F² thereon, by the cams f' and f² on the driving-shaft C. These cams are grooved cams, and the levers F' and F² are provided with pins or friction-rollers to fit in the grooves. The crimping-dies G and H have severally sliding parts g, h, which fit in suitable grooves in the parts G, H, so that the parts g, h may move independently of the dies G, H. The die-pieces G and H fit in suitable holes or grooves cast or otherwise formed in the heads F and F², and their ends abut against the ends of the hollow screw-plugs G', H', securely fixed in the heads F, F², so that the dies G, H can withstand the requisite pressure to form the crimps a^2 in the fence-wire. The movable piece or slide g of the die G extends up through the hollow plug G', and its upper end abuts against the adjustable stop or screw g', securely fixed in an arm or projection, g², on the head F. A spring, g³, is interposed between the stop g' and the sliding clamp-bar g, so as to force the clamp or slide g down. This spring should be a flat spring, and it may be secured to an arm or projection, g⁴, on the head F. The movable piece or slide h of the die H in like manner extends down through the hollow screw-plug H', and it is connected at its lower end with a pivoted arm, h', having a spring, h², which serves to force the slide h up, so as to clamp the fence-strand and barb between itself and the opposing clamp or slide g. The two slides h, h are connected together at their lower ends by a cross bar or pin, h³, so that both of them may be operated by a single spring lever or arm, h', the end of said lever being forked and fitting over this pin h³. A fixed stop, h⁴, limits the upward movement of this lever or arm h'. A pivoted stop or cam, h⁵, provided with a spring, h⁶, to keep it in position, is inserted between the head F² and the arm h' to withdraw the slides h with the dies H. As the lever F' swings the head F² around on its pivot, the pawl or cam h⁵ slips off the shoulder h⁷ and permits the spring h² to force up the slide h. As the head F² makes its upward stroke, the spring-arm h' and the slide h, actuated thereby, will follow up, and as at this time the pivoted stop or cam h⁵ is slipped off or by the flat shoulder h⁷ the slide h will be forced farther up than the die H, so as to project beyond it and clamp and hold the barb while it is being cut off and coiled around the fence-wire. When the head F² makes its further upward stroke to cause the die H to form the crimp in the fence-wire, the further

upward movement of the arm h' being arrested by the stop h^4 , so that the pivoted stop or cam h^5 can pass over the projection h^6 , the spring h^6 then restores said cam h^5 to its position, as shown in Fig. 4, so that when the head F^3 makes its downstroke the slide h will be withdrawn with the die H . When the barb-wires $a' a'$ are first fed diagonally across the strand-wire a , the spring-actuated slides g and h , as the levers F' and F^2 close together, clamp and hold the barb and strand wires together, while the further movement of the lever F' , the head F of which carries the knives E' , causes the two barbs to be severed from the barb-wires. The moment the barbs are severed the coiling heads or shafts K K' K^2 wrap the two ends of each barb in opposite directions around the fence-wire a . The two coiling-heads K and K^2 have a coiling-finger, k , at their adjoining ends, and the middle coiling-head, K' , has a coiling-finger, k , at each end, so that it can wrap one end of each of the two barbs, wrapping them both of course in the same direction. The two left-hand coiling-heads, K and K' , have large central openings, as shown in Figs. 11 or 14, so that barbs, after being secured to the wire a , can pass through them. The clamps or slides g and h serve to support the fence-wire and hold it stationary while the coiling-heads are wrapping the barbs around it. This, however, is more easily and perfectly done by reason of both ends of the barb being simultaneously wrapped in opposite directions by the coiling-heads. While the coiling is being done the dies G and H remain some distance from the wire a , so as to be out of the way of the coiling-fingers and the ends of the barb as they are carried around, as shown in Figs. 5 to 8. As the barb is fed or projected diagonally across the fence-wire a , and as the barb is held in this diagonal position after being severed until caught by the fingers k of the coiling-heads, it will be wrapped spirally around the fence-wire a . The coiling-fingers k are provided with grooves or notches k' for the barb to fit or lie in, so that as the barb is wrapped around, the ends of the barb will be inclined or drawn from their diagonal to a right-angle direction to the fence-wire a , as shown in Fig. 7. The distance between the grooves or shoulders k' of two contiguous coiling fingers which operate on the same barb should of course be the length of the coils on the wire a , or the longitudinal distance between the opposite points of the same barb. By this means the middle portion of the barb will lie diagonally or spirally across the fence-wire a , while an approximately right-angle coil around the fence-wire a will be formed near each extremity of the barb, and the barb-points will project at right-angles to the fence-wire, as described in said Patent No. 303,406. The coiling-fingers k are of course preferably made detachable from the coiling heads, and they may be conveniently and rigidly held in place by means of a groove or recess cut in the inner periphery of the hollow coiling-heads, and a clamp, k^2 , and

screw k^3 , as shown in Figs. 11 and 13. The right-hand coiling-head, K^2 , should be provided with a stationary or non-revolving guide, K^4 , for the fence-wire, which may be conveniently attached to and supported by an arm or bracket, K^5 , on the frame. The clamps g and h are made narrow, as shown in Figs. 5 to 10 and 16, so that the ends of the contiguous coiling-fingers can come sufficiently close together to properly catch the barb ends and still not strike said clamps, which hold the barb and fence-wire as the coiling is being done.

As will be observed from Fig. 4, the knives E and E' are so located in relation to each other and to the die G that when the head descends far enough to cut off the barb, the die G is brought into or almost into contact with the wire a , so that in this position said die would interfere with the wrapping of the barb around the fence-wire. The parts are located or arranged in this way to prevent the necessity of carrying the knife E' much beyond the edge of the fixed knife E , as would be the case if the lower end or face of the die G were located farther up on the head F and the head required to descend correspondingly farther to bring the die into operation after the coiling is done. To get the die G , therefore, out of the way of the coiling fingers, the head F , after descending to cut off the barb and to clamp it between the spring-slides g and h , immediately makes an upward movement to raise the die G out of the way, the spring g^3 serving to press the slide g down against the barb and the opposing slide h . After the coiling is completed the head F is again forced down by its operating-cam, and the dies G g H h form the crimp or kink a^2 in the fence-wire. In forming this crimp it will be observed from Figs. 8 and 9 that the face of the die or slide g projects slightly beyond the face of the die G , and that the die H projects beyond the die h . The dies G and H press against the coils of the barb, while the die g presses against the middle portion of the barb, and the die h withdrawing or yielding as the die g descends, the kink or bend a^2 is formed in the fence-wire a , and at the same time the middle portion of the barb is pressed down into the hollow of the bend and lies spirally or diagonal therein. After the crimp is thus formed and the barb completed the heads F and F^3 are withdrawn and the wire a fed forward the distance of two barbs by the feed-wheel, as two barbs are put on at once, and then the barb-wires $a' a'$ are again fed across to form two more barbs, and so on. After the crimp is formed in the barb the slide g is drawn up, with the die G , by means of a spring-pawl or catch, g^4 , pivoted on the head F , engaging a notch or recess, g^5 , in said slide g , as shown in Fig. 4. As the head F ascends, and just before it makes its downstroke to cut off the barbs, the arm of this pawl g^4 strikes against a fixed stop, g^6 , on a standard, g^7 , of the frame and releases the slide g , so that its spring g^3 may force it down to clamp the barb and

fence-wire. The slide g is not retracted with the die G when the head F makes its upward stroke after cutting off the barb, because when the barb is cut off the head F does not descend quite far enough to cause the pawl g^5 to catch in the notch or recess in the slide g . Pivoted spring-clamps L serve to hold the barb-wires $a' a'$ stationary and to keep a tension on said wires while allowing them to be fed forward by the feeding device.

M is a trough or vessel for holding oil or other liquid, through which the fence-wire is drawn for the purpose of lubricating the wire and rendering its passage through the machine free and easy. A fixed grooved clamp, m , and a movable grooved clamp, m' , mounted on this vessel M , serve not only to immerse the wire a in the liquid in the vessel, but also to put or keep a tension upon the wire a during its passage through the machine. The movable clamp m' is supported and operated by a lever, m^2 , to which it is attached, and which is pivoted at m^3 to the vessel M , and carries on its outer arm a weight, m^4 . By moving the weight in or out on this arm the tension may be increased or diminished as desired. The coiling-heads K and K^2 are driven in one direction and the coiling-head K' simultaneously in the opposite direction by means of a pivoted segment, N , operated by a cam, N' , on the shaft C , through gear n on the shaft n' , which intermeshes with the teeth n^2 on the segment, the gears $n^3 n^4 n^5$ on said shaft n' and the gears $n^6 n^7$ on the coiling-head shafts $K K^2$, which intermesh with said gears $n^3 n^5$, and the gear n^8 on the coiling-head shaft K' , which meshes with an intermediate gear interposed between the gears n^4 and n^8 so as to revolve the head K' in the opposite direction from the heads K and K^2 .

P is a spring having a curved surface or saddle, p , on its end to keep a proper tension on the barbed wire between the barbing devices and the feed-wheel. The spool, or rather its holder, A' , is supported on a shaft, O , journaled on the brackets or arms O' of the frame, and one end of the shaft is square, so as to cause the spool A' to revolve with it. The spool A' is caused to slide back and forth on the shaft O , so as to wind the barbed wire evenly on the spool by means of a non-revolving double-threaded hollow sleeve, o , and a traveler, o' , which is mounted upon the spool-frame A' . The sleeve o is supported on the bracket O' . The end of the shaft O , which fits in this sleeve, should be round, if the shaft is made to extend into the sleeve. The shaft O is driven from the shaft B^8 by means of a sprocket-wheel, O^2 , thereon, and a chain leading to the sprocket-wheel O^3 on the shaft O . It should be observed that as the vibration of the segment N communicates a motion first in one direction and then in the other to the gear n on the shaft n' , said gear n is not secured rigidly to said shaft, but fits loosely thereon, and it is connected to said shaft n' so as to operate the same in one direc-

tion only by means of a ratchet, n^9 , secured rigidly to the shaft n' , and a pawl, n^{10} , pivoted to the collar n^{11} , which is secured to a sleeve on which the gear n is fixed. The barb-wires a' pass through guides s .

I claim—

1. The combination of a coiling-head for wrapping a barb around a fence-wire, constructed and arranged to form two coils in the barb near each extremity of it and connected by its middle portion lying spirally or diagonally around the fence-wire, substantially as described, a pair of crimping-dies constructed and arranged to support the barb and fence wire at the two extreme coils of the barb, and to form a kink in the wire between those coils, and mechanism for operating the coiling-head and crimping-dies, these elements being arranged and their operating mechanism timed to first wrap and afterward crimp, substantially as specified.

2. The combination of a coiling-head, a pair of crimping-dies, each of which is made in two parts, $G g$ and $H h$, the one movable on the other, means for operating one pair of said parts to clamp the barb and fence wire, means for then operating the coiler, and means for finally operating the other pair of said parts to clamp and crimp the coiled barb and wire, substantially as specified.

3. The combination, with two oppositely-revolving coiling-heads, as $K K'$, of a pair of crimping-dies, as $G H$, provided with slides g substantially as specified.

4. The combination, with a coiling-head, of means for feeding the barb-wire diagonally across the fence-wire, knives for severing the barb, a pair of crimping-dies to form crimps in the fence-wire, and means for operating the several specified devices, the parts being arranged and timed to first feed, cut, and wrap, and then crimp, substantially as specified.

5. The combination, with a coiling-head, of means for feeding the barb-wire across the fence-wire, knives for severing the barb, a pair of fence-wire crimping-dies, and means for operating the several specified devices, the parts being arranged and timed to crimp the fence-wire after the barb is wrapped thereon, substantially as specified.

6. The combination, with two oppositely-revolving coiling-heads, of means for feeding the barb-wire diagonally across the fence-wire, knives for cutting off the barbs, clamps, as g and h , to hold the barb and fence wire, and dies, as G and H , to form crimps in the fence-wire, substantially as specified.

7. The combination, in a machine for applying two barbs at once to a fence-wire, of two coiling-heads, as K and K^2 revolving in the same direction and having a coiling-finger at their adjoining ends, with an intermediate coiling-head, as K' , having a coiling-finger at each end and revolving in the opposite direction, substantially as specified.

8. The combination, with coiling-heads K , K^2 , and K' , said coiling-head K' , revolving in

the opposite direction to the other two, of means for feeding two barb-wires diagonally across the fence at different points, two pairs of knives for severing the barbs, and two pairs of slides, as g h g h , for holding the barbs, substantially as specified.

9. The combination, with oppositely-revolving coiling-heads K' and K K^2 , of two pairs of dies, G H , having slides g and h , substantially as specified.

10. The combination, with tool-heads F and F^3 , of dies G and H , provided with slides g and h , knife E' , mounted in said head F , stationary knife E , and coiling-heads, as K K' , substantially as specified.

11. The combination, with coiling-heads K K^2 , of levers F' F^2 , head F , provided with knives E' E , and dies G G , with slides g g , head F^3 , provided with dies H H and their slides h h , and stationary knives E E , substantially as specified.

12. The combination, with a coiling-head, of a pair of spring-actuated slides to hold the barb and a pair of dies to form crimps or 25 kinks in the fence-wire, and barb coiled around the same, substantially as specified.

13. The combination, with means for feeding the barb-wire across the fence-wire diagonally, of a pair of knives to sever the barb-wire, 30 two oppositely-revolving coiling-heads having fingers provided with grooves or shoulders to wrap the barb about the fence-wire and wrap the barb into substantially two right-angle coils united by the spiral or diagonal 35 middle portion of the barb, and a pair of dies adapted to support the fence-wire and barb at such coils and to bend or kink the same between them, substantially as specified.

14. The combination, with a means for 40 wrapping a barb spirally around a fence-wire, of a pair of dies constructed and adapted to support the barb and fence-wire at the two extreme coils of the barb and to bend or crimp the fence-wire between the two extreme 45 coils of the barb, substantially as specified.

15. The feed-wheel B , provided with arms or jaws b' , and movable arms or jaws b^2 , and a cam, as b^4 , for operating said movable jaws b^2 , substantially as specified.

50 16. The feed-wheel B , provided with forked arms b , jaws b' , pivoted jaws b^2 , and cam b^4 , substantially as specified.

17. The combination, with wheel B , having arms b , jaws b' , and pivoted jaws b^2 , of a fixed 55 cam-collar, b^4 , and mechanism for intermittently revolving said wheel, substantially as specified.

18. The combination, with a barb-fence machine, of a trough or vessel, M , provided with 60 a pair of wire-clamps, m m' , to immerse the

wire in the liquid in said vessel and put a tension upon the same, substantially as specified.

19. The combination, with a barb-fence machine, of trough M , provided with clamps m m' , and a pivoted lever, m^2 , having weight m^4 , for operating said clamp m' , substantially as specified.

20. The combination, with trough M , of clamps m m' , lever m^2 , and weight m^4 , substantially as specified.

21. The combination of vibrating feed-lever D , provided with jaws d and d' , said jaw d' being pivoted to jaw d , and link d^3 , connected to said pivoted jaw for operating said feed-lever and at the same time opening and closing said jaw d' , substantially as specified.

22. The combination of feed-lever D , provided with jaw d and pivoted jaw d' , with link d^3 , connected to said pivoted jaw, said 80 jaw d' having a lip or projection, d^1 , and setscrew d^2 , to adjust the feed-stroke, substantially as specified.

23. The combination, with a coiling-head, of dies G and H , and slides g and h , and heads F and F^3 , said slide g being provided with a notch or recess, g^6 , and said head F , having a spring-pawl, g^5 , whereby said slide g is retracted, substantially as specified.

24. The combination, with two oppositely-revolving coiling-heads, of a pair of dies adapted to form crimps or bends in the fence-wire between the two extreme coils of the barb, said dies having each a narrow sliding part adapted to hold the barb after it is severed and while it is being coiled, and means for operating said sliding parts independently of said dies, substantially as specified.

25. The combination, with feed-lever D , of jaws d and d' , link d^3 , lever d^4 , link d^8 , and 90 lever d^9 , substantially as specified.

26. The combination, with duplicate feed-levers D , having jaws d and d' , of links d^3 , levers d^4 , links d^8 , and lever d^9 d^7 , and cam d^{10} , for operating the same, substantially as 105 specified.

27. The combination, with means for coiling a barb around a fence-wire into two coils connected by the middle portion of the barb lying spirally or diagonally across the fence-wire, substantially as shown and described, of means for forming a kink or crimp in the fence-wire between the two coils of the barb, and operating mechanism for these devices, whereby the barb is first coiled and the crimp 115 afterward effected, substantially as specified.

LEWIS W. CONNELL.
